CLAIM

The ornamental design for a protective glove, as shown and
described.

DESCRIPTION

FIG. 1 is a perspective view of a protective glove.

FIG. 2 is a front view of a protective glove.

FIG. 3 is a rear view of a protective glove.

FIG. 4 is a left side view of a protective glove.

FIG. 5 is a right side view of a protective glove.

FIG. 6 is a top view of a protective glove; and,

FIG. 7 is a bottom view of a protective glove.

The broken lines shown are included for the purpose of
illustrating a portion of the protective glove that forms no
part of the claimed design.

The stippling in the drawings is for shading purposes only.
Although shown in the context of a right hand glove, an
embodiment of the present invention also may be incorpo-
rated in a left hand glove.
